ACTIVATOR FOR OXYGEN BATHS

Richard Neu, Dessau-Rossbau, Anhalt, Germany,
assignor, by mesne assignments, to "Unichem"
Chemikalien Handels A.-G., Zurich, Switzerland,
a corporation of Switzerland

No Drawing. Application January 15, 1937, Serial No. 120,715. In Germany January 15, 1936

5 Claims. (Cl. 167—86)

It is known that certain metals or metal salts respectively made of peroxides, perborates, per-sulfates, percarbonates and the like are able of liberating the bound oxygen. For this purpose there are in first line the salts of copper, manganese, nickel, cobalt, iron and silver to be considered, either alone or in combination with organic acids. However, owing to the alkaline reaction of the baths, we see some inconveniences 5 in the formation of unsoluble metal-hydroxides hampering the development of the oxygen. Moreover the bath, by the precipitation of tinged metal-hydroxides grows mean-looking and turbid, the flaky precipitate deposits itself on the 10 body of the bathing person and causes a soiling and damaging of the bath-towels. With certain catalysts the development of oxygen goes on so slowly that the liberating of the oxygen takes several hours. Certain other catalysts which, 15 at the contrary, cause a very strong development of oxygen, show the drawback that they decompose also themselves during the gas-development while separating metal-hydroxides or metal oxy-hydrates respectively, so that the bath becomes mean-looking. Among the compounds of the aforescribed kind there are the heavy metal salts of sulfonated fatty stuffs and particularly of fatty alcohols. Those metal salts distinguish themselves e. g. by not letting so easily escape 20 the oxygen from the surface of the bath-liquid, if they are added to the perborate, i. e. by retaining it in a stiff froth-cover which even after complete decomposition of the perborate persists for a good while, allowing thus a perfect utilization 25 of the oxygen. Attempts had already been made to attain the aforesaid effect also by special additions of frothing substances such as saponin, tannin or albumin; but until now we know nothing about the attaining, by one and the same 30 substance, a satisfactory gas-development and frothing in a bath free of metal-precipitates.

Now it has been found that an excellent oxygen- and froth-developer, which at the same time prevents the separation of metal-hydroxide or metal-oxide-hydrate respectively, is obtainable in converting heavy metal salts of sulfuric acid derivatives of higher molecular organic compounds of the general formula

50 or respectively, the salts of those organic sulfuric acid derivatives with amines into water-soluble complex compounds. In the mentioned formula R means any higher molecular hydrocarbon residue 55 due of no less than 6 to 30 carbon atoms, X means the atoms or atom groups S, O, COO, OCO, NR'', SO₂, NR''SO₂, CONR'' and the like or it may be left out, whereas R' means an alkylene residue eventually substituted by hydroxyl- or halogen- groups or, if Y be absent, also an arylene residue;

R'' means hydrogen or any hydrocarbon residue, Y means sulfur or oxygen or it may be absent, and n represents the numbers 1 or 2. As sulfuric acid derivatives of higher molecular organic compounds of the above formula the following compounds may be cited: the sulfuric acid ester of the dodecyl-alcohol, the sulfuric acid ester of the selachyl-alcohol, the ω -butyl-ether of the decyl- ω' -sulfuric acid ester, the sulfuric acid ester of the 1,10-decandiol-monooacetate, the ω -hexyl-thio-ether of the hexyl-thio-sulfuric acid ester, the ω -sulfuric acid ester of the caprylic acid-butyl-amide, the ω -sulfuric acid ester of the decansulfonic acid phenyl amide, the di-sulfuric acid ester of the ricinolic alcohol, further the ω -lauryl- or, respectively, the naphthenyl ether of the ethane-sulfonic acid, the ω -butyl- or, respectively, the cyclohexyl ether of the decan-1-sulfonic acid, the ω -phenyl-thiohexane sulfonic acid, the cetyl-thio-ethane sulfonic acid, the dodecyl-sulfonic ethane sulfonic acid, the N-lauryl-amido-ethane sulfonic acid, the N-diethyl-acetic-amide sulfonic acid, the N,N-dodecyl-p-toluol-sulfonyl-amido-ethane sulfonic acid, the oleic acid ester of the hydroxyethane sulfonic acid, the N-cetyl sulfonic sulfonic acid, the naphthenic acid amide of the amido-ethane sulfonic acid, the ω -phenyldecan sulfonic acid.

As heavy metal salts to be employed to form 30 the heavy metal salts from the sulfuric acid derivatives of the higher molecular organic compounds, the following inorganic or organic salts may be cited: the chlorides, nitrates, sulfates, acetates etc. of the copper, manganese, nickel, 35 cobalt, iron and silver etc.

For the converting with the above mentioned organic sulfuric acid derivatives there are in first line the alkylamines, the hydroxy-alkylamines, amino alcohols or their ethers, amino-alkyl-polyalcohols, amino-alkyl-thiols etc. to be considered. But under certain circumstances also cyclic amines may be applied. Thus the following amines are to be considered: propylamine, tri-ethyl-amine, benzyl-amine, mono-di- and tri-ethanol-amine, hydroxy-benzyl-amine, ethoxy-ethyl-amine, tri-ethoxy-tri-ethyl-amine, glucamine, β,β' -diamino-diethyl-sulfide, 1-amino-ethane-thiol, cyclohexyl-amine, pyridine, piperidine, methyl-piperidine, aniline and the like.

The advantages of the new oxygen-developers consist, on the one hand, in a quiet and uniform gas-developing from peroxides or per-salts in aqueous baths, without any decomposition of the latter and without precipitating any metal compounds. Furthermore, owing to the froth formed during the gas-development there occurs no or but a very slow escaping of the liberated oxygen, so that its perfect utilization is secured while

the treatment of single body-parts is practicable without ado. Moreover one needs comparatively little amounts of water to prepare the oxygen baths, as the froth-cover, owing to the formation of oxygen-bearing froth-bubbles, may be brought in direct contact with the body-surface. The claimed complex compounds may be produced and applied either in a solid or in a dissolved form.

10 *Example 1*

27 weight parts of sodium salt of the dodecyl-sulfuric acid ester are dissolved in ethyl-alcohol while warming, whereupon they are mixed with an aqueous solution, concentrated as much as 15 possible, of 12.5 weight parts of copper-sulfate. Now by heating for some time a greenish substance is precipitated, which after an addition of 45 weight parts of triethyl-amine dissolves itself in forming a dark-blue solution. This 20 solution is then concentrated in vacuo and mixed and pulverized with sodium tetraborate, sodium sulfate, sodium chloride or with other salts, eventually in adding some perfumes. The thus resulting light-green powder gives a clear solution 25 in water and no precipitation will occur if mixed with soda lye.

Instead of the dodecyl-sulfuric acid ester one 30 may likewise apply the equivalent amount of cetyl-, oleyl-, glycer-mono-alkyl- or glycer-mono-acyl sulfuric acid ester and convert with the corresponding amounts of chlorides, nitrates, sulfates, acetates etc. of metals, which form complex compounds.

35 *Example 2*

The condensation-product obtainable in the usual way from 30 weight parts of oleic acid chloride and 14 weight parts of methyl-taurin, is changed over into the barium salt and mixed 40 in the warmth to form a concentrated aqueous solution with 28 weight parts of cobalt sulfate dissolved in 60 weight parts of water. The precipitating barium-sulfate is filtered off and the clear filtrate is concentrated in vacuo to about 45 half its volume. The obtainable aqueous concentrate of the cobalt salt of the oleyl-methyl-amido-ethane sulfonic acid is then mixed with 27.5 weight parts of γ -amino- α,β -propylene-glycol, whereupon it is slightly warmed until complete 50 solution and then concentrated in vacuo. After cooling the dry complex cobalt compound may eventually be mixed with salts as indicated in Example 1.

Instead of the cobalt salt of the oleyl-methyl-amido-ethane sulfonic acid the salts of the cetyl-sulfuric acid, of the lauroyl-hydroxy-ethane sulfonic acid or of the α -dodecyl-ether of the β -hydroxy-propane- γ -sulfonic acid of metals forming complex compounds, may in the same way 60 be converted with amines.

By means of the aforesaid developers for oxygen-baths it is possible practically to decompose unlimited amounts of peroxides or persalts in aqueous baths.

65 I claim:

1. An activator for a bath containing active oxygen-yielding compounds which comprises a product resulting from the reaction of an amine selected from the group which consists of alkyl amines, hydroxy alkyl amines, amino alcohols, ethers of amino alcohols, amino alkyl-poly al-

cohols, amino alkyl thiols, and cyclic amines, with a salt of a heavy metal selected from the group which consists of the metals copper, manganese, nickel, cobalt, iron, and silver; said salt being a sulfuric acid derivative of an organic compound of high molecular weight having the general formula:

wherein R represents a high molecular weight 10 hydrocarbon radical containing from 6 to 30 carbon atoms; X represents a radical selected from the group which consists of S, O, COO, OCO, NR'', SO₂, NR''SO₂, and CONR''; R' represents a radical selected from the group which 15 consists of the alkylene radicals, hydroxyl substituted alkylene radicals, halogen substituted alkylene radicals, and arylene radicals; R'' represents a radical selected from the group which 20 consists of hydrogen and hydrocarbon radicals; Y represents a radical selected from the group which 25 consists of sulfur and oxygen; n represents a number selected from the group which consists of 1 and 2; and L represents a number selected from the group which consists of 0 and 1. 25

2. An activator for oxygen baths comprising a complex compound of the copper salt of the dodecyl-sulfuric-acid ester with tri-ethyl-amine.

3. An activator for oxygen baths comprising a complex compound of the manganese salt of 30 the glycero-mono-dodecyl-sulfuric acid ester with tri-ethanol-amine.

4. An activator for oxygen baths comprising a complex compound of the cobalt salt of the oleyl-methyl-amido-ethane sulfonic acid with 35 γ -amino- α,β -propylene-glycol.

5. A bleaching bath comprising an aqueous solution of an active oxygen-yielding compound selected from the group which consists of peroxides, perborates, persulfates, and percarbonates which contains, as an additional ingredient, an activator which comprises a product resulting from the reaction of an amine selected from the group which consists of alkyl amines, hydroxy alkyl amines, amino alcohols, ethers of amino alcohols, amino alkyl poly alcohols, amino alkyl thiols, and cyclic amines; with a salt of a heavy metal selected from the group which 40 consists of the metals copper, manganese, nickel, cobalt, iron, and silver, said salt being a sulfuric acid derivative of an organic compound of high 45 molecular weight having the general formula:

wherein R represents a high molecular weight 55 hydrocarbon radical containing from 6 to 30 carbon atoms; X represents a radical selected from the group which consists of S, O, COO, OCO, NR'', SO₂, NR''SO₂, and CONR''; R' represents a radical selected from the group which 60 consists of the alkylene radicals, hydroxyl substituted alkylene radicals, halogen substituted alkylene radicals, and arylene radicals; R'' represents a radical selected from the group which 65 consists of hydrogen and hydrocarbon radicals; Y represents a radical selected from the group which 70 consists of sulfur and oxygen; n represents a number selected from the group which consists of 1 and 2; and L represents a number selected from the group which consists of 0 and 1. 70
